UNITED STATES PATENT OFFICE.

ALBERT KRAUTH, OF HAMILTON, OHIO.

PAPER FEEDING AND SEVERING MECHANISM FOR MANIFOLDING-MACHINES.

1,098,510.

Specification of Letters Patent.

Patented June 2, 1914.

Application filed May 31, 1913. Serial No. 770,954.

To all whom it may concern:

Be it known that I, ALBERT KRAUTH, a citizen of the United States, residing at Hamilton, in the county of Butler and State 5 of Ohio, have invented certain new and useful Improvements in Paper Feeding and Severing Mechanism for Manifolding-Machines, of which the following is a specification.

10 My invention relates to manifolding apparatus, and primarily to a type of machine wherein invariable constant lengths of paper are advanced and severed from a continuous sheet or strip. In this class of machine 15 usually a plurality of rolls of paper are journaled in parallelism within a casing with their ends brought over a writing table and gripped between feeding mechanism for advancing the strips, relatively superposed as 20 a unit. Manifolding material is inserted between the portion of the sheets over the writing table whereby an entry made upon the uppermost or exposed sheet will be transferred to the sheets beneath the same. 25 The sheets or strips usually contain a pre-printed blank or text in multiple successive numbers, with all the sheets of a series corresponding relatively so that the blanks can be disposed in registry over each other. 30 Therefore with the sheet subdivided into equal length intervals, a measured movement of advance is required to a delivery point, so that it can be severed from its succeeding interval at the divisional line or 35 spacing separating the same and such measured advance is especially essential when the severing is automatically accomplished and progressively after the advance of the paper within a cycle or period of operation 40 of the propelling mechanism, and the succeeding length or interval properly positioned over the writing table.

The apparatus disclosed herein is manually operated by a crank handle which is 45 arrested or checked in its motion at the limit of a measured advance of the paper by engaging a rigid stop element and releasable therefrom for a second operation. Thus constant invariable lengths can be 50 sued from the machine without requiring the operator to observe the advance of the paper, or delicate manipulation. This invention, however, is primarily concerned and directed to the severing mechanism and 55 its particular adaptation to manifolding machines, operated progressively after a

measured advance of the paper, and within a measured cycle of the propelling mechanism therefor.

The principal object of my invention is 60 in the provision of an oscillating cutter member having a cutter blade mounted thereon circumferentially, with its cutting edge angular longitudinally from one end toward the other so that in its arc of movement it will be progressively engaged with a relatively stationary cutter blade or edge, 65 approximately in a diametric line of the arc of cutter travel.

Another object of my invention is to provide a segmental knife supporting drum 70 rotatively mounted and yieldingly urged toward a stationary cutter, the ends of the drum having circumferential guiding means adapted to engage with the stationary cutter or an abutment to limit the urging movement of the drum in its normal position or a non-cutting movement of cutter blade mounted upon the drum.

Various other features of my invention 80 relate to the combination of cutter and paper feeding mechanism in relative geared connection with a propeller handle for a positive operation of the parts when active but of an arrangement permitting independent 85 operation of both feeding and severing mechanism progressively one after the other within a measured stroke of the propeller handle, all of which will be more fully set forth in the description of the accompanying 90 drawings forming a part of this specification, in which:—

Figure 1 is a side elevation of my apparatus. Fig. 2 is a central vertical section through the forward portion thereof illustrating the feeding and severing mechanism. Fig. 3 is a side view opposite from that shown in Fig. 1 of the forward portion of the apparatus. Fig. 4 is a section on line 4—4 of Fig. 2. Fig. 5 is a detail plan view 100 of the rotative cutter shown in Figs. 1 and 2. Fig. 6 is a cross section through a modified cutter.

The claims of this invention are founded upon structural improvements over that 105 shown in a pending application filed February 27, 1913, Serial No. 751,048. The general organization of the machine is in many respects similar to that shown and described in said pending application especially as it 110 relates to the paper supporting and feeding mechanism and therefore reference will only

be made to such features as are necessary to aid in a clear understanding of this invention.

1 represents the side frames of the machine supported upon a base 2. These side frames may be of sectional or integral form, between which the webs of paper are supported. The ends of each web of paper are brought together over a writing table in the usual manner and fed between the feeding rolls 3 and 4. The roll 3 having its axis supported in a rigid bearing, and the roll 4 has its axis supported in sliding bearings in the side frame and yieldingly urged toward the axis of roller 3 for maintaining the peripheries of the rolls 3 and 4 in frictional contact with each other, to grip the paper threaded between them.

At one end of the upper roll 4 a gear 5 is provided in mesh with a gear 6 fixed to the axis of the lower roll for positively rotating the rolls in unison and prevent slippage of the rolls in a paper feeding operation. The pinion 6 of the lower roll is in mesh with a pinion 7 fixed upon a sleeve 8, see Fig. 4, said sleeve being suitably journaled in a bearing formed in one of the side frames. The pinion 7 is adapted to mesh with the mutilated master gear 9 fixed to the shaft 10, said shaft extending across and journaling in both of the side frames. As will be seen from Fig. 1, a portion of the teeth of gear 9 are cut away to produce an idle period to the feeding rolls during a portion of a complete rotation of the gear 9, the purpose being to arrest the motion of the feed rolls or discontinue the advance of the paper during a severing operation, which severing operation progressively follows the discontinuance of the feed of the paper in making a complete revolution of the gear 9.

One end of shaft 10 is provided with a two-part crank handle 11, and it may be made of extensible form, so that the handle portion 12 can be moved in a direction away from the axis of the handle or shaft 10 for releasing the handle from the stop projection 13, with which the handle engages to limit or check its rotation, and definitely locate the end of an operative cycle necessary to produce the measured advance and severance of an interval length of paper. A spring is utilized to normalize the handle portion 12 after it clears the projection 13, which is shown in dotted lines, Fig. 1. A handle of this character has been described in detail in the aforesaid pending application, but as far as the aspect of this invention is concerned any kind of propelling mechanism may be employed for producing a measured stroke or advance of the paper and operate the severing mechanism within a cycle of an invariable nature, for delivering the cut lengths of paper heretofore specified. The opposite end of the shaft 10 has

a mutilated gear 14 fixed thereto, see Figs. 3 and 4, its teeth adapted to intermesh with the pinion 15 fixed upon the pintle or axis 16 of the rotating knife drum 17. The non-toothed portion of the mutilated gear 14 is relatively proportioned to the toothed portion of gear 9 and the toothed portion of said gear 14 with the non-toothed portion of the gear 9 and relatively arranged so that when gear 9 is transmitting motion to gear 14 or pinion 7, the gear 14 will rotate idly and when a reverse period exists, gear 15 will be rotated while gear 7 is idle, during a rotative interval of the main driving shaft 10. This prevents an advance of the paper toward the cutters, which might have a tendency to choke the cutters or disturb the accuracy of the feed or alignment.

The cutter mechanism herein comprises an oscillating or rotating cutter member having a removable or renewable cutter blade, which cooperates with a relatively stationary cutter bar. The cutter mechanism in detail comprises a segmental drum 17, its ends provided with annular flanges or disks 19 from which the pintles 16 forming the axis of the drum project. These are suitably journaled in bearings formed in the side frames, and to one of which the gear 15 is fixed, as heretofore set forth. The bearings for the pintles of the drum are of an elongated form horizontally with bearing blocks 21 slidably mounted within said bearing slots, each engaged by a spring for forcing the drum toward the stationary cutter bar 22. The cutter bar 22 is rigidly mounted between side frames each end thereof having an arcuated flange 23 engaging respectively with a disk 19 of the rotative knife drum to limit or confine the movement of the drum toward the stationary cutter during a normal or non-cutting position of the drum and maintain the parts in a relative operative position under pressure toward each other. The periphery of the drum, as shown in Fig. 2 is provided with a knife blade 24 secured thereon by screws 25, rendering the same readily removable for grinding or renewal without dismantling the drum, driving mechanism or machine. The cutting edge of the blade 24 is angled longitudinally from one end toward the other, as illustrated in Fig. 5, whereby the cutting edge will be progressively engaged with the cutting edge of the stationary cutter bar 22, to produce a shear cut when the drum is rotated.

The blade 24 is made of comparatively thin metal and is longitudinally adjustable to aline the same with the cutting edge of the stationary cutter member. The drum at several points throughout the length of the blade is provided with a series of adjusting screws 35, bearing against the blade 24. This enables a delicate adjustment of the blade after which it is rigidly clamped in position.

5 by the screws 25. In a normal position of the cutters their cutting edges are separated from each other to provide an opening approximately tangent with the feeding rolls, so that as the paper is advanced it will be directed between the cutters in position to be severed. The drum has an oscillating action, and is moved forwardly toward the stationary cutter by the gearing heretofore described, and as soon as the last tooth of the mutilated or segment gear 14 is released from the teeth of gear 15, the drum will be quickly returned to its normal position by a spring 33 having one end fixed to the pintle, 10 and its opposite end to the frame of the machine. The limit of reverse movement of the knife drum may be designated by a stop or a complete release of the spring tension, this feature being optional as far as the features of this invention are concerned.

20 It is manifest that the knife drum may be provided with a plural number of peripheral segments for supporting a number of knife-blades, and its operation rotative instead of oscillating, in which a successive knife edge is serially advanced toward a cutting position within the province of this invention, and the knife-blade may be of such a form as illustrated in the modified view, Fig. 6, in which it is secured upon an angular edge of the segment of the drum instead of on its periphery.

25 In Fig. 4 I have illustrated mechanism for releasing or separating the feeding rolls from their peripheral contact, the mechanism comprising a rock shaft 26 journaled in the side frames, and in this instance, one end is journaled within the sleeve hub 8 of the gear 7, and the opposite end is provided 30 with a handle 27 for manually rocking said shaft. 28 represents a pinion fixed on the shaft 26 in mesh with a pinion 29 fixed on the rock-shaft 30 journaled in the side-frames. The rock shaft 30 has a pair of pins 31, each is adapted to respectively engage one end of a pair of bell crank arms 32 loosely pivoted on the axis of the lower roll 3 and having their upper ends positioned to engage the axis of the upper roll 4 to raise 35 the same when the shaft 26 is rocked.

40 Having described my invention I claim:—

1. A device of the nature disclosed combining a stationary cutter member, an oscillating drum member yieldingly urged toward the cutting edge of said stationary cutter member a circumferential cutter blade removably mounted on said drum member having an angular cutting edge longitudinally and circumferentially movable with 45 said drum to progressively engage said stationary cutter member in a diametric plane with its axis.

2. A device of the nature disclosed combining a rotative circumferential blade supporting member yieldingly urged toward

5 the cutting edge of a stationary cutter member, a cutter blade circumferentially mounted upon said supporting member a stationary cutter member disposed tangent to said cutter blade, with its cutting edge longitudinally in a diametric plane with the axis of said cutter blade, and means for rotating 70 said blade supporting member.

3. A device of the nature disclosed combining an oscillating cutter blade supporting drum having an annular guiding flange at each end thereof, a cutter blade circumferentially mounted upon said drum, a stationary cutter blade disposed tangent to said cutter blade and engaged by said annular 75 flanges, and having its cutting edge longitudinally in a diametric plane with the axis of said cutter blade, and means for positively moving said cutter blade across the cutting edge of said stationary cutter member. 80

4. A device of the nature disclosed combining a pair of coacting paper feeding rolls, a pair of coacting cutter members arranged in close proximity to said paper feeding rolls comprising a circumferential rotative cutter blade having its cutting edge angular longitudinally and yieldingly urged toward the cutting edge of a stationary cutter member, and a stationary cutter blade 90 having its cutting edge longitudinally in a diametric plane with the axis of said rotative cutter blade, and propelling means for said feeding rolls and rotative cutter blade positively rotating the same in relative successive intervals. 95

5. A device of the nature disclosed combining a rotative circumferential blade supporting member, a cutter blade circumferentially mounted upon said supporting member, means for longitudinally adjusting the cutting edge of said blade at various points, a stationary cutter member disposed tangent to said cutter blade, with its cutting edge longitudinally in a diametric plane with 105 the axis of said cutter blade, and means for rotating said blade supporting member. 110

6. A device of the nature disclosed combining a rotative cutter member having an angularly disposed cutting edge longitudinally and provided with an annulus at each end, each peripherally engaged with a non-rotative cutter member, a non-rotative cutter member having its cutting edge longitudinally in a diametric plane with the axis of 120 said rotative cutter member, and means for yieldingly urging the cutting edges of said members toward each other. 115

7. A device of the nature disclosed combining a rotative cutter member annularly engaged with a non-rotative cutter member and with its cutting edge in longitudinal plane with the periphery thereof, a non-rotative cutter member having its cutting edge longitudinally in a diametric plane 130

with the axis of said rotative cutter member and means for yieldingly urging one of said cutter members toward the other.

8. A device of the nature disclosed combining an oscillating cutter member having an annular guide flange at each end thereof and a longitudinal cutting edge approximately coincident with each annular flange radius, a non-rotative cutter member having its cutting edge disposed diametrically longitudinally with the axis of said oscillating cutter member, a crank handle, transmission elements connecting said crank handle and oscillating cutter member for positively moving its cutting edge across its opposing cutting edge, and means for automatically returning said oscillating cutter member to normal.

9. A device of the nature disclosed combining a pair of coacting paper feeding rolls, a pair of coacting cutter members adjacently parallel with said feeding rolls, comprising an oscillating cutter member having an annular guide flange at each end thereof and a longitudinal angular cutting edge approximately coincident with each annular flange radius, a non-rotative cutter member, its cutting edge disposed diametrically with the axis of said oscillating cutter member and engaged with said guide flanges, a crank handle, transmission elements connecting said crank handle and oscillating cutter member and said feeding rolls for operating the same in relative successive intervals in a functioning direction upon each cycle of said crank handle, and means for automatically reversely moving said oscillating cutter member to normal.

10. A device of the nature disclosed combining paper feeding mechanism operated in predetermined cycles for feeding a continuous web of paper to serially advance invariable constant lengths thereof, and paper severing mechanism operated successively to each paper length advance to sever the same from the web, comprising a non-rotative cutter member, a rotative cutter member provided at each end with an annular flange engaged with said non-rotative cutter member, and means for yieldingly urging said rotative cutter member toward said non-rotative cutter member.

11. A device of the nature disclosed combining a pair of coacting paper feeding rolls, coacting paper severing members, comprising a rotative cutter member having its ends annularly and yieldingly engaged with a non-rotative cutter member, a non-rotative cutter member, propelling mechanism for said paper feeding rolls and rotative cutter member, and means intervening said paper feeding rolls and rotative cutter member for intermittently rotating said cutter member successively of a paper feeding interval.

12. A device of the nature disclosed combining a pair of coacting paper feeding

rolls, coacting paper severing members, comprising a rotative cutter member annularly engaged at each end with a non-rotative cutter member and yieldingly urged toward the same, propelling mechanism for rotating said rolls to advance a predetermined length of paper and successively thereafter rotate said cutter member to bring into coöperation the cutting edge of said rotative cutter member with said non-rotative cutter member to sever the predetermined length of paper from its continuous web.

13. A device of the nature disclosed combining a pair of coacting rolls yieldingly urged toward each other and positively rotated in opposing directions, a master gear for rotating said rolls having a toothed contour of a circumferential length at its tooth pitch diameter equal to a predetermined length of paper advance for each revolution of said gear with the remainder of its contour non-toothed, capable of providing an active and inactive interval for said rolls in each cycle of operation of said master gear, a rotative cutter having a cutting edge longitudinally and provided with an annulus at each end yielding in constant engagement with a non-rotative cutter member, a non-rotative cutter member having its cutting edge longitudinally in a diametric plane with the axis of said rotative cutter member, a segmental gear for rotating said rotative cutter member intermittently relative during the inactive paper feeding interval of said master gear to coöperatively engage the cutting edge of said rotative cutter member with the cutting edge of said non-rotative cutter member, and means for automatically normalizing said rotative cutter members.

14. A device of the nature disclosed combining a rotative cutter member and a non-rotative cutter member having their cutting edges yieldingly urged toward each other, a pair of gears for positively rotating said rotative cutter member, one thereof having a portion of its contour non-toothed for releasing said cutter member during an interval in each cycle of said gear, and means for automatically reversely rotating said cutter member during its released intervals.

15. A device of the nature disclosed combining a rotative cutter member and a non-rotative cutter member each having coöperating cutting edges, and transmission mechanism for said rotative cutter member having a segmental gear as an element thereof to release said rotative cutter member during a portion of a cycle of said gear.

16. A device of the nature disclosed combining a rotative cutter member and a non-rotative cutter member each having coöperating cutting edges, transmission mechanism for said rotative cutter member having a

segmental gear as an element thereof to release said rotative cutter member during a portion of the cycle of said gear, and means for reversely rotating said rotative cutter member during its released interval to normalize the same.

17. A device of the nature disclosed combining a rotative cutter member having its cutting edge longitudinally in plane with its axis, a non-rotative cutter member having its cutting edge longitudinally in a diametric

plane with the axis of said rotative cutter member, and means for yieldingly urging one of said cutter members toward its companion cutter member, to a restraining limit for coöperation.

In testimony whereof, I have hereunto set my hand.

ALBERT KRAUTH.
